UNITED STATES PATENT OFFICE.

OTTO F. HALMER, OF LOS ANGELES, CALIFORNIA.

FILM-DEVELOPER.

1,381,548.

Specification of Letters Patent. Patented June 14, 1921.

Application filed April 29, 1920 Serial No. 377,542.

To all whom it may concern:

Be it known that I, OTTO F. HALMER, a citizen of the United States, residing at Los Angeles, in the county of Los Angeles and State of California, have invented new and useful Improvements in Film-Developers, of which the following is a specification.

This invention is a film developer and has for its object the provision of an improved construction whereby a roll of films may be supported within a receptacle containing developing fluid in such manner as to be moved back and forth through the fluid for causing intimate contact of all parts of the roll of films with the developing medium.

Further objects of the invention will be readily understood from the following description of the accompanying drawings, in which—

Figure 1 is a perspective view of a film developer constructed in accordance with the invention.

Fig. 2 is a transverse section on the line 2—2 of Fig. 1.

Fig. 3 is a longitudinal section on the line 3—3 of Fig. 1.

Fig. 4 is a side elevation of the end of one of the supporting rods for the roll of films.

The improved developer consists essentially of a receptacle 1 for the developing fluid, a supporting head 2 removably mounted upon the open end of the receptacle, and supporting rods 3 extending from said head into the receptacle and arranged to have the respective ends of a roll of films 4 secured thereto, the supporting head carrying mechanism for rotating said supporting rods so as to wind the roll of films from one supporting rod to the other and thereby move the roll of films through the developing fluid in the receptacle.

The supporting head upon the open end of the receptacle 1 is shown as comprising crossed bars 5 and 6 forming a spider received over the end of the receptacle and having an annular band 7 arranged to embrace the outside of the receptacle secured to the downwardly bent ends 8 of said crossed bars. Retaining lips are arranged to engage the inner surface of the receptacle 1, these lips being shown as spring lips 9 comprising downwardly bent ends of a strip 10 secured to the under side of one of the crossed bars of the supporting head. By

the arrangement, as thus described, the supporting head may be readily slipped over the open end of the receptacle 1 and as readily removed therefrom, the spring lips 9 holding the supporting head comparatively rigid upon the receptacle.

The supporting rods carried by the head, as thus described, are, preferably, journaled in one of the crossed bars of the head, say the bar 5, and are shown for this purpose as provided with bearing collars 11 resting against the upper surface of the bar 5. Pinions 12 are fixed upon the supporting rods above the bearing collars, and the ends of the rods, preferably, terminate in pins 13 arranged to be engaged by the fingers for separately rotating the respective supporting rods. The supporting rods may be journaled in brackets 14 between the pinions and the actuating pins, these brackets being shown as secured to the bar 5.

The connection between the ends of a roll of films and the respective supporting rods may consist of an elongated slot 15 formed in each of the respective supporting rods, the latter being hollow to form an interior space 16 throughout the length of said slots. The ends of these slots at the lower ends of the supporting rods are, preferably, cut away, as shown at 17, in order to provide a guideway to assist in readily positioning the end of a film roll within the hollow supporting rod.

When attaching the end of a film roll to the supporting rod the end of the film is, preferably, reversely bent upon the film, as shown at 18, and this bent end is then inserted in the hollow rod with the film projecting through the slot 15 and the bent portion of the film engaging the walls of said slot for connecting the film to the supporting rod. The opposite ends of a film roll are thus secured to the respective supporting rods and the supporting rods are arranged to be simultaneously rotated for rolling the film off of one supporting rod and on to the other. For this purpose the following described mechanism may be employed.

A stub shaft 19 is mounted upon the supporting head of the developer as by extending the shaft through the crossed bars 5 and 6 and retaining it in position by a nut 20 having threaded engagement with the end of the shaft. A pinion 21 is loosely slidably journaled upon the stub shaft and is ar-

ranged to mesh with pinions 12 at its opposite sides so that turning of the pinion 21 will rotate the supporting rods 3 to wind and unwind the film from one supporting 5 rod to the other.

The pinion 21 is provided with a suitable handle 22 mounted upon a crank arm 23 for reversely rotating said pinion to reversely wind the roll of films. As previously stated, the pinion 21 is slidable upon stub shaft 19 by which arrangement the pinion is adapted to be moved along the stub shaft so as to disengage pinions 12, as clearly shown in Fig. 3. This movement of the pinion 21 is, preferably, controlled by a lever 24 having a slotted end 25 loosely received upon the shaft 19 beneath the pinion 21. The lever is pivoted at 26 in a suitable bracket 27 so that the outer end of the lever 20 may be engaged by the finger for swinging the lever to raise and lower the pinion 21. The pivotal mount 26 of this lever is, preferably, a frictional pivot so arranged that the lever will remain in either position to which it is swung for retaining the pinion 21 in either operative or inoperative position. Sliding movement of the pinion 21 upon the stub shaft 19 may be limited by a pin 28 having a threaded engagement 29 with the end of the stub shaft, so that by removing said pin the pinion 21 may be completely removed from the supporting head of the developer as may be found convenient during transportation of the developer.

35 In operation the supporting head and rods of the developer are removed from the receptacle 1 when it is desired to secure a roll of films to the supporting rods and the pinion 21 is moved to its inoperative position. The ends of the film roll may then be inserted in the respective ends of the supporting rods, as previously described, and the supporting rods be independently rotated by their pins 13 for initially rolling the 45 film roll upon the supporting rods. The supporting head is then positioned upon the receptacle 1 with the roll of film immersed in the developing fluid in the receptacle and the pinion 21 is moved to its operative 50 position so that by subsequent rotation of this pinion in reverse directions the roll of films may be wound and unwound from one supporting rod to the other so as to draw the films back and forth through the developing medium.

Various changes may be made without

departing from the spirit of the invention as claimed.

What is claimed is:

1. A film developer comprising a receptacle for the developing medium, and rotatable supporting rods extending within said receptacle in spaced relation, said supporting rods being tubular and slotted upwardly from their lower ends and adapted 65 to receive the respective ends of a film so that the film may be wound from one of the supports to the other.

2. A film developer comprising a receptacle for the developing medium, a support- 70 ing head removably placed over the end of said receptacle, supporting rods journaled on said head and extending into the receptacle, said supporting rods arranged to engage a film so that the latter may be wound 75 from one supporting rod to the other, and means upon said supporting head for simultaneously rotating said supporting rods.

3. A film developer comprising a receptacle for the developing medium, a support- 80 ing head removably placed over the end of said receptacle, supporting rods journaled on said head and extending into the receptacle, said supporting rods arranged to engage a film so that the latter may be wound 85 from one supporting rod to the other, a manually rotated member upon said supporting head arranged to engage said supporting rods for simultaneously rotating the latter, and means for shifting said manually rotated member out of engagement with said supporting rods.

4. A film developer comprising a receptacle for the developing medium, a supporting head removably placed over the end of 95 said receptacle, supporting rods journaled on said head and extending into the receptacle, said supporting rods arranged to engage a film so that the latter may be wound from one supporting rod to the other, pinions upon said supporting rods, a pinion journaled upon said supporting head between said first mentioned pinions and arranged to engage said pinions for rotating the same, and means for sliding said second 105 mentioned pinion lengthwise of its axis out of engagement with said first mentioned pinions.

In testimony whereof I have signed my name to this specification.

OTTO F. HALMER.
